UNITED STATES PATENT OFFICE.

GUSTAV EDMUND REINHARDT, OF LEIPZIG-CONNEWITZ, GERMANY,
ASSIGNOR TO JOHN BERNARD MERCER, OF LONDON, ENGLAND.

APPARATUS FOR GATHERING SHEETS OR SIGNATURES OF BOOKS.

SPECIFICATION forming part of Letters Patent No. 731,221, dated June 16, 1903.

Application filed February 6, 1903. Serial No. 142,186. (No model.)

To all whom it may concern:

Be it known that I, GUSTAV EDMUND REINHARDT, a subject of the Emperor of Germany, residing at Waisenhausstrasse, Leipzig-Connewitz, in the Empire of Germany, have invented new and useful Improvements in Apparatus for Gathering Sheets or Signatures of Books or other Publications, of which the following is a specification.

This invention relates to improvements on the apparatus for gathering sheets or signatures of books or other publications described in the specification of the prior patent granted to John Bernard Mercer and bearing number 628,829, dated July 11, 1899.

In the apparatus described and claimed in the specification of above-mentioned patent suitable apparatus is employed for taking a single sheet or signature from each of the piles of same and delivering them in succession to a traveling belt to which an intermittent step-by-step motion is imparted.

According to the prior patent above referred to a suction apparatus is employed for removing the bottom sheet or signature from each of the piles and bringing it to such position that it can be readily seized by grippers, which carry it over the traveling band and release same, so that it falls upon that part thereof which is at that moment under the grippers in question.

The present invention relates more especially to improvements in the above-mentioned parts of the collecting or gathering apparatus and is illustrated in the accompanying drawings, in which—

Figure 1 is a vertical section of the part of the apparatus embodying such features. Fig. 2 is a plan view of the part of Fig. 1, illustrating the improvements in the suction or sheet-removing device; and Fig. 3 is a vertical section, on an enlarged scale, of the same feature, but showing it in its intermediate lowered position, as hereinafter described.

It will be seen that the grippers, consisting of a pair of arms 1 2, are carried at the bottom end of a lever 3, mounted on a shaft 4, capable of turning in bearings in the frame 14 of the machine. A reciprocating rotary movement is imparted to the lever 3, carrying the

grippers, by means of an eccentric 5, mounted on the driving-shaft 6 and connected by rod 7 to an arm 8, which is also mounted on the shaft 4. The bottom arm 1 of the grippers is stationary in relation to the lever 3, carrying same, while the top arm 2 of such grippers can turn in relation to the latter. Such arm 2 is extended beyond the point where it is pivoted to lever 3 and connected to toggle or jointed levers 9 10, which also reciprocate with lever 3. The extension of arm 2 of the grippers is continued beyond the pivot of toggle-lever 9 and connected by a spring 11 to the upper toggle-lever 10. Fixed stops or abutments 12 13 are arranged on the frame 14. A pin 15 is mounted toward the upper end of lever 3, carrying the grippers, and is capable of sliding transversely through same, such pin being brought into contact with the fixed stop 12 at the extremity of the forward movement of the lever.

It will be seen that the action of the apparatus is as follows: The eccentric 5 through rod 7 and arm 8 will impart reciprocating motion to lever 3, carrying the grippers. This forward movement of lever 3 brings the grippers into the position for seizing the sheet or signature which has been removed from the bottom of the pile b; the suction apparatus to be hereinafter described, and at the extreme forward movement the pin 15 coming into contact with the fixed stop 12 will be forced backward, and its rear end coming into contact with the upper toggle-lever 10 will in its turn force the latter backward until the lower toggle-lever 9 closes the grippers, thus seizing the sheet. The spring 11 will retain the grippers in the closed position, and the continued action of eccentric 5 will cause lever 3 to return to the extreme backward position, thus bringing the back of the upper toggle-lever 10 into contact with the fixed stop 13, and so force same forward, and through the lower toggle-lever 9 open the grippers, thus releasing the sheet, which will fall upon that part of the intermittently-traveling endless band 16, which is immediately below same. The spring 11 will then act so as to hold the grippers open until eccentric 5 causes lever 3 to again travel forward in order to

seize a new sheet or signature, when the action will be repeated.

A retaining-hook 35 is pivoted on the toggle-levers 9 10 and can be turned so as to be brought over a pin 36 on the lever 3, carrying the grippers, whereby the action of the toggle-levers to open and close the latter during the backward and forward travel of lever 3 will be prevented, this being necessary in order to prevent sheets from all the piles being seized by the respective grippers at the commencement or end of the running of the machine, at which period the machine minder or attendant has to engage or disengage such hooks from their pins so as to bring the grippers into or throw them out of operation in succession.

The suction apparatus for removing the under sheet or signature from each of the piles of same consists of a sucker-bar 17, capable of a rotary-reciprocating movement on a pivot 18 and actuated through levers 19 20 by a cam 21, also mounted upon the driving-shaft 6, such cam being constructed so that the sucker-bar 17 has two distinct movements imparted thereto in its downward travel, the object of this being to first carry the bottom sheet or signature removed from the piles of same to the necessary position to be seized by the grippers 1 2 and then when such sheet or signature has been seized to make a further descent, so that the backward movement of such grippers will not cause the sheet or signature it carries to rub over the edges of the suckers 22. By this means the suckers are prevented from becoming worn and thereby interfering with their action in properly seizing the bottom sheet or signature under the influence of the vacuum produced in such suckers by any suitable form of suction apparatus to which they are connected.

Fig. 3 shows the sucker-bar 17 in its first or intermediate lowered position, when the sheet it has caused to descend is ready to be seized by the grippers, and the broken line 23 shows the position of such bar when it has descended to its full extent. The front end of a bar 24 is curved upward and when the sucker-bar 17 is in its lowest position projects through a slot 25, formed in the latter, so as to extend upward beyond the top of the suckers 22, and by coming into contact with the under side of the removed sheet or signature thus supports same free from the edges thereof and keep it out of rubbing contact therewith during the backward movement of the grippers.

The downward movement of the sucker-bar might cause more than one sheet or signature to be carried to the position for being seized by the grippers, and in order to prevent this I arrange brushes 26 in the path of travel of the outward free end of the sheet or signature, so that the rubbing contact between such free end and said brushes will produce a dragging or retarding action, such as to separate the top superposed sheet or sheets

from the bottom sheet acted upon by the suckers 22, and thus prevent same following such bottom sheet in its movement to present itself to the grippers.

In order to return any sheet or sheets retained by the brushes 26 during the downward movement of the sucker-bar 17 to the proper position to be seized by such suckers at their next upward movement and also to correct any tendency which the sheets at the under side of the pile may have to sag when the bottom sheet is removed, I employ the arrangement shown in the drawings and which consists in a bar 27, to which a reciprocating rotary motion is imparted. For this purpose the bar 27 is mounted on a pivot 28, carrying a pinion 29, gearing with a rack 30, capable of sliding in guides 31 and formed on a bar, and the lower end of which is connected through a link 32 to a pivoted lever 33, the opposite end of which is acted upon by a cam 34, mounted on the driving-shaft 6. The action of this cam is to cause the bar-carrying rack 30 to move downward in its guides 31 when the sucker-bar 17 is in its lowered position, and thus cause the bar 27 to turn upward and thereby raise any sheet retained by the brushes 26 to its proper position on the under side of the pile of sheets or signatures and hold it there until the sucker-bar again rises and by its suckers seizes the next sheet or signature to be delivered, when (through the continued action of cam 34) the movement of the rack 30 will be reversed and bar 27 moved downward, so as to leave the sucker-bar 17 free for its next descent with the fresh sheet it has secured.

In order to indicate to the machine minder or attendant when one or more of the series of gripping apparatus is or are not from any cause efficiently operating, a visible signal 37 is employed, which is mounted so that it can swing on a pivot 38 and is operated by the grippers when same are acting efficiently, but remains stationary when the grippers are inoperative. For this purpose a series of visible signals or disks 37, numbered successively to correspond with the particular pair of grippers each belongs to, are mounted so that they can swing on the pivot 38, and when the grippers 1 2 move forward a projection thereon will carry the signal to the position shown in full lines in Fig. 1, while in the backward movement of such grippers the edges of the sheet held by same coming in contact with the lower end of the arm carrying the signal 37 will carry the latter back to the position shown in broken lines in such figure. It will therefore be seen that if the grippers move backward without carrying a sheet the signal 37 will remain in its forward position, and consequently out of line with the other signals which have been duly actuated by the backward movement of their respective grippers, and the attendant will consequently at once see that one or more of the

grippers is or are not operating and by the number on the particular signal disk or disks at once locate the particular grippers at fault.

What I claim as my invention, and desire

5 to secure by Letters Patent, is—

1. The combination of a pivoted reciprocating lever, means for reciprocating said lever, a pair of grippers, one of which is pivoted, mounted on the free end of said lever, toggle-jointed levers connected with the pivoted gripper for operating the latter, fixed stops at the extreme points of oscillation of the reciprocating lever, for operating the toggle-levers and pivoted gripper, a pivoted sucker-bar for drawing down the bottom sheet of a pile of signatures, and brushes fixed at the front of the pile of signatures, for separating the superposed sheets from said bottom sheet, to present the latter to the grippers.
- 15 2. The combination of a pivoted reciprocating sucker-bar for acting upon the bottom sheet of a pile of signatures in the machine, a traveling band for receiving said signatures, a pair of grippers for seizing and conveying said bottom sheet to said band, means for reciprocating and operating said grippers, in coöperation with said sucker-bar, a fixed bar for holding the bottom sheet clear of the suckers during the backward movement of
- 20 3. said grippers and sheet, and means for imparting two successive movements to the sucker-bar in its descent, substantially as specified.
- 25 3. The combination of a pivoted reciprocating

ing sucker-bar for acting upon the bottom 35 sheet of a pile of signatures, and brushes fixed at the front of the pile of signatures, for arresting and separating from said bottom sheet the superposed sheets, as the bottom sheet is carried down by the movement of the sucker-bar, substantially as specified.

4. The combination of a pivoted reciprocating sucker-bar having a slot 25, a fixed upwardly-curved bar beneath the sucker-bar, projecting through said slot as the sucker-bar 45 descends, a pivoted reciprocatory supporting-bar at the front of the pile of signatures, means for oscillating the sucker-bar, and means for oscillating the supporting-bar in synchronism with the movements of the sucker-bar.

5. The combination with pivoted reciprocating grippers, a pivoted reciprocating sucker-bar for separating the bottom sheet of a pile of signatures, and a pivoted reciprocating supporting-bar, of a visual signal carried on 55 a pivoted oscillating rod in the path of the bottom sheet separated by said grippers, to indicate the operativeness or non-operativeness of said grippers, substantially as specified.

In testimony whereof I have signed my name to this specification in the presence of two subscribing witnesses.

GUSTAV EDMUND REINHARDT.
